UNITED STATES PATENT OFFICE.

THOMAS J. DEMOREST, OF GARFIELD, WASHINGTON.

COMPRESSED-AIR WATER-ELEVATOR.

SPECIFICATION forming part of Letters Patent No. 657,192, dated September 4, 1900.

Application filed November 27, 1899. Serial No. 738,404. (No model.)

To all whom it may concern:

Be it known that I, THOMAS J. DEMOREST, a citizen of the United States, residing at Garfield, in the county of Whitman and State of Washington, have invented a new and useful Compressed-Air Water-Elevator, of which the following is a specification.

This invention relates to compressed-air water-elevators; and it has for one object to provide an automatically-operating apparatus of this character having simple and reliable means for elevating the water or other fluid from wells or reservoirs to its point of use. To this end the invention primarily contemplates simple and efficient means for automatically controlling the valves in connection with a novel arrangement of piping whereby the supply of compressed air will be automatically controlled and also exhausted at intervals to permit of the intermittent filling of the tank or tanks and the forcible discharge of water through the main delivery-pipe.

A further object of the invention is to provide an improved arrangement of parts whereby a continuous and uniform stream may be constantly discharged through the main delivery-pipe during the operation of the apparatus.

With these and many other objects in view, which will more readily appear as the nature of the invention is better understood, the same consists in the novel construction, combination, and arrangement of parts herein-after more fully described, illustrated, and claimed.

The fundamental features of the invention which insure the automatic supplying and exhausting of the air to the tank or tanks are necessarily susceptible to a variety of modifications without departing from the spirit or scope of the invention; but the preferred embodiment of the improvements is shown in the accompanying drawings, in which—

Figure 1 is a vertical longitudinal sectional view of a compressed-air water-elevator embodying the improvements contemplated by the present invention, showing the different parts of the apparatus in position to provide for the discharge of water from the upper movable receiving-tank while the lower sta-

tionary tank is filling. Fig. 2 is a view similar to Fig. 1, showing the positions of the different parts of the apparatus reversed—namely, to provide for discharging the liquid from the lower receiving-tank while the upper tank is filling. 55

Like numerals of reference designate corresponding parts in both figures of the drawings. 60

In carrying out the present invention a single receiving-tank for the water or other liquid has the main working parts of the apparatus associated therewith; but to insure a continuous and uniform discharge of the liquid through the delivery-pipe there is preferably employed a pair of liquid-receiving tanks 1 and 2, which are arranged one above the other, so as to occupy as little space as possible and permit of the apparatus being placed in bored or drilled wells. Both of the liquid-receiving tanks 1 and 2 are designed to be submerged in the water or liquid to be elevated and are of any size or shape, according to the desired capacity of the apparatus and the nature of the well or reservoir in connection with which the same are employed. The tank 1 may be referred to as a "buoyant" tank, inasmuch as the same is designed to rise and fall in the water or liquid in which it is submerged, and as the essential features of the invention are embodied in the parts associated with this tank reference will first be made thereto independent of the action of the lower stationary tank 2 and the parts 75 combined therewith to provide for the continuous discharge of the water. 80

The vertically-movable receiving-tank 1 is provided in the bottom thereof with a water-inlet opening 3, which is designed to be covered and uncovered by an inwardly-opening inlet-valve 4. The water-inlet valve 4 preferably consists of a flat valve plate or disk 5, having a gasket or equivalent packing 6 to provide a water and air tight closure when the valve is seated upon the bottom of the tank. The inwardly-opening valve 4 is located inside of the receiving-tank 1, within the bottom portion thereof, and has fitted to the center thereof a depending valve-stem 7, 90 arranged to work in the guide-tube 8, rigidly supported centrally within the water-inlet

opening 3, and providing means, in connection with the stem 7, for retaining the valve 4 in proper working position and causing the same to evenly seat and unseat itself during the action of the apparatus. Inasmuch as the tank 1 is submerged in the water or liquid to be elevated, the release of air-pressure within the tank permits the valve 4 to open inwardly to uncover the inlet-opening 3, thereby admitting a supply of water to the interior of the tank, and through the means hereinafter described this water or liquid is subsequently forced out of the tank through the water-discharge pipe 9. The water-discharge pipe 9 is fitted in the top of the vertically-movable tank 1 and depends therein to a point near its bottom or in sufficiently-close proximity to the valve 4 to permit of the tank 1 being practically emptied entirely of the water therein, and to accommodate the vertical movement of the tank 1 without interfering with the free discharge of water therefrom the discharge-pipe 9 is provided exterior to the tank and above the top thereof with a telescopic joint 10. The exterior telescopic joint 10 of the discharge-pipe 9 essentially consists of the fixed and movable pipe-sections 11 and 12, closely registering one within the other and having a sliding fit, so that the movable section 12, forming a portion of the discharge-pipe carried by the tank 1, is permitted to freely work up and down within the fixed section 11 as the tank rises and falls. The upper fixed pipe-section 11 of the telescopic joint 10 has extended from the upper end thereof a valve-chamber 13, within which is arranged an upwardly-opening gravity check-valve 14, which prevents return flow of water through the discharge-pipe 9 into the tank when the water is relieved from the pressure of the compressed air, and to provide for the outlet of the water from the discharge-pipe 9 and the telescopic joint thereof the check-valve casing or chamber 13 is coupled at its upper end to the main water-delivery pipe 15, which extends above the well or reservoir to the point of use.

The fixed and movable sections 11 and 12 of the telescopic pipe-joint 10 are provided in adjacent walls with the normally-disaligned exhaust-ports 16. The disalignment of these ports is maintained when the vertically-movable tank 1 is in its lower position; but when said tank is elevated the said ports are brought into register or alignment, so that the air contained within the tank and its pipe will find the proper vent, so as to admit of the refilling of the tank. The complete venting of the vertically-movable receiving tank 1 is accomplished through the medium of a vent-tube 17, extending longitudinally through the discharge-pipe 9 and provided at its upper end with a hook or similar connection 18, engaging with a fixed point of attachment on or within the fixed section 11 of the telescopic pipe-joint 10, thereby providing means for holding the vent-tube 17 stationary

in a relatively-fixed position, while at the same time not interfering with the vertical movement or the buoyant action of the tank 1. The vent-tube 17 is provided at a point near the telescopic pipe-joint 10 with a vent-opening 19, which permits of the exhaust of air from the vent-tube and its consequent escape through the exhaust-ports 16 of the telescopic joint. The vent-tube 17 of the discharge-pipe is provided in its lower end with an elbow 20, extending around the lower end of the discharge-pipe 9, and with an upstanding inlet-limb 21, which projects upwardly within the tank 1 to a point near the top thereof and is provided at its upper end with a valve-seat 22, adapted to receive thereon an exhaust-valve 23, fitted to the lower end of the valve-stem 24, the upper end of which valve-stem 24 has fitted thereto an air-cut-off valve 25, arranged to work over an interior valve-seat 26, located within an air-inlet chamber 27. The stem 24, carrying the valves 23 and 25, is steadied in its movements by a guide 28, fitted in the top portion of the tank 1. The air-inlet chamber 27 communicates at its lower open end with the interior of the tank 1 at the top of the latter and has coupled to its upper end one end of the compressed-air-supply pipe 29, the other end of which is connected with a suitable air-compressor or air-pump which provides for supplying air under pressure to the apparatus. The compressed-air-supply pipe 29 is preferably provided contiguous to its connection with the air-inlet chamber 27 with a coiled flexible or spring section 30, which will readily contract and expand to permit of the free vertical movement of the movable or buoyant tank 1.

To insure a proper operation of the apparatus, there is preferably associated with the same an overbalance device which serves to hold the tank a sufficient length of time in either of its extreme positions to insure a proper action of the apparatus. This overbalance device may be substituted by any equivalent device that will accomplish the same result—namely, to hold the tank 1 stationary at the limit of each movement for a certain period—but the preferable form of device for accomplishing the desired end is shown in the drawings and substantially consists of a tilting weight-lever 31 and a rolling or shifting weight 32, supported by said lever and capable of a shifting movement from one end thereof to the other. The tilting weight-lever 31 is pivotally supported intermediate its ends, as at 33, on a fixed point of attachment and is provided with a longitudinal groove or way 34 to form a retaining-guide for the rolling or shifting weight 32. At a point contiguous to and at one side of its pivot 33 the pivoted weight-lever 31 has slidably connected thereto, by means of a loop or equivalent connection 35, the upper end of an adjusting-rod 36, the lower end of which is fixedly attached to the air-inlet chamber or other part of the tank 1, so that as the tank

rises and falls the lever 31 will be tilted or oscillated with a consequent shifting of the weight 32 thereon.

In the action of the tank 1 and the parts 5 associated therewith, as just described, it may be assumed that the tank 1 is filled with water or other liquid, and is thereby in its lowered position, as shown in Fig. 1 of the drawings. In this position the water-inlet 10 valve 4 is closed upon its seat to provide for covering the water-inlet opening 3, and the exhaust-valve 23 rests upon the seat at the upper end of the inlet-limb 21 of the vent-tube 17, thereby cutting off communication 15 between this tube and the interior of the tank 1, while at the same time holding the air-cut-off valve 25 elevated above its seat, and thus opening communication between the tank and the compressed-air-supply pipe 20 29. The compressed air is therefore free to pass from the air-compressor or air-pump through the pipe 29 and its flexible or spring section 30 into the air-inlet chamber 27 in the top portion of the tank 1. The pressure 25 of air exerted upon the body of water in the tank 1 forcibly expels this water through the discharge-pipe 9 and its telescopic joint 10 into the main water-delivery pipe 15, which carries the water to the point of use. When 30 the tank 1 has been nearly emptied, and is therefore necessarily filled with air, the buoyancy thereof causes the same to rise, which movement brings the air-cut-off valve 25 to its seat, thus cutting off the further supply 35 of compressed air, while at the same time elevating the exhaust-valve 23 and uncovering the inlet end of the vent-tube 17. With the closing of the air-cut-off valve 25 the water-check valve 13 necessarily closes and prevents 40 the return flow of water, and the exhaust-ports 16 of the telescopic pipe-joint 10 come into register and permit of the exhausting or venting of the air within the interior of the tank 1 as the water rushes in through 45 the valved water-inlet opening 3 to refill the tank. During the upward movement of the tank 1 the lever 31 is tilted in a direction to shift the weight 32 to one end thereof, and the weight in such position will, in connection 50 with the buoyancy of the tank, hold the same in its elevated position until the same is again filled, after which the weight of the water therein will cause it to again descend and shift the various working parts to their 55 original positions to admit of the supply of compressed air for forcibly expelling the water through the discharge-pipe and its connections.

As already explained, the stationary tank 60 2 below the tank 1 is utilized to insure a continuous discharge of water through the main water-delivery pipe 15, and reference will now be made to the conjoint action of the two tanks and the parts combined with the 65 stationary tank. The said stationary tank 2 is provided at the bottom thereof with a water-inlet opening 37, covered and uncover-

ed by an inwardly-opening valve 4^a, constructed and operating in the same manner as the valve 4, associated with the tank 1, and at the top thereof the stationary tank 2 has communicating therewith an air-inlet chamber 38, having a branch-pipe connection 39 with the main compressed-air-supply pipe 29 above the point of connection of the pipe 70 with the air-inlet chamber 27 for the movable tank 1. The air-inlet chamber 38, communicating with the top of the stationary tank 2, has arranged therein a valve-seat 39^a, above which works an air-cut-off valve 40, fitted to 75 the upper end of a vertically-reciprocating valve-stem 41, the lower end of which stem is arranged in the path of the laterally-deflected tappet-arm 42 at the lower end of the exhaust-valve stem 43. The exhaust-valve 80 stem 43 works through a vent-port 44 in the top of the tank 2 and has a suitable loose connection 45 at its upper end with the bottom of the movable tank 1, so that the movements of this latter tank may be utilized to 85 provide for controlling the air cut-off and exhaust valves of the tank 2. The exhaust-valve stem 43 has fitted thereto within the tank 2 an exhaust-valve 46, arranged to cover and uncover the vent-port 44 in the manner 90 to be presently explained.

To provide for the discharge of water from the lower stationary tank 2, the same has depending therein a water-discharge pipe 47, provided at a suitable point with a gravity 100 vertically-movable check-valve 48, and having a branch-pipe connection 49 with the main water-delivery pipe 15. It will be observed that when the tank 1 is in its lowered position and the water or other liquid discharged 105 therefrom in the manner described the exhaust-valve 46 is held below the port 44 and the cut-off valve 40 is seated so as to cut off the supply of air from the tank 2, thus permitting the valve 40^a to open and the said 110 tank to fill with water. Upon the upward movement of the tank 1, as the same is about emptied of its water, the said movement of the tank 1 closes the vent-port 44 and at the same time brings the tappet-arm 42 on the 115 exhaust-valve stem into contact with the valve-stem 41 of the air-cut-off valve 40, thereby elevating this valve above its seat and permitting the compressed air to enter the tank 2 to forcibly expel the water therefrom through the pipe 47 and the branch pipe 120 49 into the main delivery-pipe 15. It will thus be seen that the construction just described in effect constitutes a double-acting water or liquid elevating apparatus, inasmuch as one tank fills with water at the same 125 time the other is emptying, thus causing a continuous and even stream to discharge through the delivery-pipe 15.

In carrying out the invention it may be 130 found desirable to change or modify the parts without affecting the operation just described, and it will therefore be understood that various changes in the form, proportion,

and minor details of construction may be resorted to without departing from the principle or sacrificing any of the advantages of this invention.

5. Having thus described the invention, what is claimed as new, and desired to be secured by Letters Patent, is—

1. In a liquid-elevating system, the combination with a vertically-movable tank, and 10 means for intermittently supplying aeriform fluid thereto, of a liquid-eduction pipe, and a telescopic connection between said eduction-pipe and the tank and having members provided with vent-ports, one of said members 15 being shiftable with the tank to alternately bring the vent-ports into registration and disaligned relation, substantially as described.
2. In a liquid-elevating system, the combination with a vertically-movable tank, and 20 means for intermittently supplying aeriform fluid thereto, of a liquid-eduction pipe, a telescopic connection between said eduction-pipe and the tank and including members provided with eduction-ports, and a separate 25 valved vent-pipe sustained independently of the tank and discharging into the telescopic connection, substantially as described.

3. In a liquid-elevating system, the combination with a vertically-movable tank, and 30 means for intermittently supplying aeriform fluid thereto, of a liquid-eduction pipe, a telescopic connection between said eduction-pipe and the tank and including members provided with eduction-ports, a vent-pipe sustained 35 independently of the tank and discharging into the telescopic connection, and air inlet and exhaust valves operable to alternately control the admission of air to the tank and the exhaust of air therefrom through 40 the vent-pipe, substantially as described.

4. In an apparatus of the class described, a vertically-movable receiving-tank having a bottom valved liquid-inlet, a liquid-discharge pipe extending within the tank and having 45 an exterior telescopic joint provided with air-exhausting ports, and means, controlled by the movement of the tank for automatically providing for the supply of air to the tank and the exhaust thereof through said exhaust-ing-ports, substantially as set forth.

5. In an apparatus of the class described, a buoyant liquid-receiving tank provided with a bottom valved inlet, a discharge-pipe extending within the tank and provided with an 55 exterior telescopic pipe-joint having air-exhausting ports, a vent-tube communicating with the telescopic joint of the discharge-pipe and with the interior of the tank, and means, controlled by the movement of the 60 tank, for automatically providing for the supply of compressed air thereto and the exhaust of the air through the vent-tube, substantially as set forth.

6. In an apparatus of the class described, 65 a vertically-movable submerged receiving-tank provided at the bottom with a valved liquid-inlet, a discharge-tube extending with-

in the tank, and provided exterior thereof with a telescopic joint having air-exhausting ports, a compressed-air-supply pipe having a 70 connection with the tank, a vent-tube communicating respectively with the interior of the discharge-pipe and the top portion of the receiving-tank, and air cut-off and exhaust valves automatically adjusted by the movement of the tank to provide for controlling the supply of compressed air and the exhaust thereof through the vent-tube, substantially as set forth.

7. In an apparatus of the class described, 80 a vertically-movable receiving-tank provided at the bottom with a valved liquid-inlet, a discharge-pipe extending within the tank and provided exterior thereof with a telescopic joint having air-exhausting ports adapted to 85 align and disalign, the fixed section of the telescopic joint having an interior check-valve and a connection with the delivery-pipe, an air-inlet chamber in communication with the tank at the top and provided with 90 an interior valve-seat, a compressed-air-supply pipe connected with said air-inlet chamber, a vent-tube suspended within the discharge-pipe from the fixed section of the telescopic joint and provided with a vent-opening 95 and having an inlet-limb extending upward within the tank to a point near the top, and a movable valve-stem carrying at its upper end a cut-off valve cooperating with the seat within the air-inlet chamber, and at its lower end an exhaust-valve working over the opening at the inlet end of the vent-tube, substantially as set forth.

8. In a liquid-elevating system, the combination with a vertically-movable tank, and 105 an eduction-pipe having a compensating connection therewith, of a vent-pipe sustained independently of and suspended partly in the tank and having an upturned limb provided with a valve-seat, an air-inlet valve, an exhaust-valve adapted to the seat of the vent-pipe, a stem connecting the two valves, and a valve-seat carried by said tank and adapted for the air-inlet valve, substantially as described.

9. In a liquid-elevating system, the combination of a vertically-movable tank, an eduction-pipe, an air-supply chamber carried by the tank and having a valve-seat, a supply-pipe to said chamber, a stationary vent-pipe 120 suspended in the tank and having a valve-seat in alinement with the seat of the air-supply chamber, and the connected inlet and exhaust valves adapted respectively to the seats of said chamber and the vent-pipe by the rise 125 and fall of the tank, substantially as described.

10. In a liquid-elevating system, the combination of the air-supply and eduction pipes, a vertically-movable tank, individual compensating connections between said pipes and the tank, means for controlling the admission of air to and exhaust from the tank, a support fixed to and upheld by said pipes over 130

the tank, an oscillatory lever pivoted centrally to said support, a weight movable freely on the lever, and a rod connected with the tank and to the lever at one side of its pivot 5 to shift the latter on the rise and fall of the tank, substantially as described.

11. In a compressed-air water-elevator, the combination of a floatable tank having a valved inlet, a stationary tank also provided 10 with a valved inlet and arranged below the floatable tank, a pressure-supply pipe, a compensating valved connection between said pressure-pipe and the floatable tank, a separate valved exhaust from the floatable tank 15 and controlled by the travel of the tank itself, a branch connection from the pressure-

pipe to a supply-chamber on said stationary tank, a valve in said chamber, a rod operatively related to the valve and connected to the movable tank, and an eduction-pipe having a compensating connection with the movable tank and a branched valved connection with the stationary tank, substantially as described. 20

In testimony that I claim the foregoing as 25 my own I have hereto affixed my signature in the presence of two witnesses.

THOMAS J. DEMOREST.
